UNITED STATES PATENT OFFICE.

WILLY ABEL, OF BERLIN, GERMANY, ASSIGNOR TO HIMSELF, AND HEINRICH WOLLHEIM, OF GRUNEWALD, NEAR BERLIN, GERMANY, AND KARL STRAUSS, OF WIESBADEN, GERMANY.

COIN-FREED APPARATUS.

No. 838,930.

Specification of Letters Patent.

Patented Dec. 18, 1906.

Application filed September 29, 1903. Serial No. 175,042.

To all whom it may concern:

Be it known that I, WILLY ABEL, engineer, a subject of the German Emperor, residing at 59 and 60 Friedrichstrasse, Berlin, in the 5 Empire of Germany, have invented certain new and useful Improvements in Coin-Freed Apparatus, of which the following is a specification.

This invention has reference to automatic 10 apparatus for vending stamps, labels, or the like which are inserted in the machine in strips or bands. It belongs to those systems wherein the power requisite for the cutting off of an individual stamp or the like 15 and for the forward movement of the band is obtained from one single source of power. By this it is to be understood that one and the same means of power—for instance, the hand-power of the purchaser or a mechanical 20 driving mechanism—causes the separation and forward feed in contradistinction to such apparatus wherein one working process is effected by the hand of the buyer and the second working process by the power of a 25 clock-work mechanism or the like.

With the hitherto-known apparatus with a unitary source of power the arrangement is such that after actuation first the forward 30 movement and then the separation of the stamp or label is effected. At the same time such movements are given to the parts which cause these two operations that during the progressive movement of said parts in the same direction both processes take place 35 consecutively. From this it may be seen that the members upon their return must travel the same path empty—i. e., uselessly—as they do on making the forward working movement.

40 My invention embodies novel features of construction, arrangement, and combination of parts, whereby important advantages in operation are attained.

The new self-vending machine is shown in 45 the drawings and, namely, as a postage-stamp-vending machine.

Figure 1 shows the arrangement of the automatic vender viewed from one side; Fig. 2, from the side opposite; Fig. 3, in plan; 50 Fig. 4, in end elevation. Figs. 5 and 6 show the changing or reversing gear for operating the separating and holding device in two positions. Fig. 7 shows the delivery-slide in

plan; Fig. 8, in side elevation with partial section. Fig. 9 is a detail view showing the 55 action of the separating and the holding device. Fig. 10 is an end elevation showing the stamp-separating device in the position it occupies when beginning the separation.

In the construction shown it is assumed 60 that the delivery device consists of a slide which after being unlocked is drawn out by the purchaser and which returns automatically. The general arrangement of the delivery-slide and of the devices moved thereby 65 can be seen best from the plan shown in Fig. 3. The delivery-slide *a*, provided with the handle *a'*, is arranged with its longitudinal direction parallel to the direction of the forward feed of the strip 1. The strip is 70 wound on a roller 2 within the casing *b* and when drawn off is guided through a groove 4 between side flanges *c*. (See Figs. 1 and 3.) The feed device *d* is connected to the slide *a* by the lever *e* in such a way that on 75 moving the latter in the direction of the arrow I (shown in Fig. 3) the said feed device *d* is moved in the direction of the arrow II, while upon the return of the delivery-slide both parts are moved in a direction opposed 80 to each other.

In Fig. 3 the part *m* of the strip 1 to be cut off is shown in the advanced position which it takes up after use of the automatic vender. At F the device is arranged for cutting off and 85 holding fast the part *m* to be cut off, the details of which will be gone into farther on. To the slide *a* there is furthermore connected a locking device *g*, which prevents the slide from going back before it is completely 90 drawn out. This locking device is first released, whereby the return of the slide is also released when the latter has been pulled completely out. A further locking device *h* prevents the withdrawal of the delivery-slide 95 prior to the insertion of the coin by means of which its release is effected. On drawing out the slide *a* the spring *i* is set or expanded. A too violent recoil of the slide when released, due to the influence of the said spring *i*, is preferably prevented by an air-buffer device K.

The devices above mentioned will now be described each in detail.

The feed device for the band can best be seen from Figs. 1 and 3. It is constructed 105 upon the basis that it shall require as little

frictional power as possible in order that it may produce the favorable distribution of power mentioned in the introduction. The strip 1, which is wound off from the roller 2 in the casing *b*, is guided through the groove 4 to the separating and holding device. The feed of the strip 1 to the length of the part *m* to be cut off, Fig. 3, is effected by the catches 5, which consist of a considerable number of 10 teeth or pins lying side by side, which are mounted to rotate upon a common axis 6 free and independent of each other. This axis is located in a sliding or oscillating part in the constructional form represented 15 on a long lever 7, which at the bottom is pivoted to the frame of the apparatus at 8, while the upper part can be swung to and fro over the feed or supply channel. The feed-lever 7 is articulated at the top at 10 20 through the arm 9 to the lever *e*, which in its turn swings round the pin 11 and engages with the other forked end 12 with the pin 13 of the slide *a*, so that on the movement to and fro of the latter a corresponding movement to 25 and fro of the part 7 with the catches 6 is caused. These latter are arranged obliquely in such a way that upon the oscillation of the lever 7 they can slide freely in the direction of the arrow II over the band-strips and more 30 especially over the perforations. If, on the contrary, the part 7 swings in the opposite direction, then the catches 5 slide freely forward till they engage with the perforations of the strip of stamps 1 and cause it to be carried along. The part 7 at the same time executes a throw or stroke which is somewhat larger than the distance of the successively-following strip perforations.

The lever 7 is preferably mounted in such 40 a way that as soon as it is guided a little beyond its central position it swings automatically into its terminal position both in the one as well as in the other direction. In the present construction the lever 7 possesses 45 for this purpose a shoulder or attachment 91, which bears against a plate-spring 92. In Fig. 1 the lever 7 is in its outermost position to the right and the spring 92 is thereby bent to the left. If the lever 7 be moved to the 50 left and if at the same time the shoulder 91 be moved somewhat beyond the central position to the left, then the spring is bent to the right, and thereby throws the lever 7 into the left terminal position. Owing to the fact 55 that a considerable number of catches 5, arranged side by side and movable independently of each other, the certainty is afforded that at least some of the catches engage with the perforations of the strip and that its further forward motion is effected without fail, even if the holes of the successively-following perforations have different positions.

As may be seen from Fig. 3, there is effected upon the forward movement of the slide in

the direction of the arrow I the idle return 55 (return without load) of the catch device 5 6 7 in the direction of the arrow II. On the contrary, during the automatic return of the slide the forward movement of the feed device will take place contrary to the direction 70 of the arrow II. Thus normally the separated portion *m*, Fig. 3, is in the advanced position. At the same time this takes up the position necessary for separation, whereby the rows of perforations are below the separating-blades. 75

The device for separating and holding fast the part to be sold may be described with reference to Figs. 2, 4, 5, 6, 9, and 10. The delivery-slide *a* has an attachment 14, which 80 acts upon a pressure-roller 15, mounted on the lever 16. Said lever 16 is loosely mounted on the axis 17 of the coin-wheel 20. A pawl 18 is pivoted to lever 16 and engages the teeth of ratchet-wheel 19. The latter is fast 85 on the axle 17 together with coin-wheel 20, so that both wheels (19 and 20) are rotated together by the pawl 18 when the lever 16 is moved from the position shown in Fig. 6 into the position shown in Fig. 5. Upon the periphery of the coin-wheel 20 there runs a roller 21. It is carried by a lever 22, which is rotatably mounted upon the shaft 23 in the standard 24. The wheel 20 has an irregular periphery formed by a series of projections and grooves spaced equidistantly. Around the shaft 23 there oscillate two arms 25, which are preferably coincident in their construction and which, if necessary, can be combined to form one common whole. As 90 these latter lie one behind the other in Fig. 4, only one of the two arms is there visible, while, as may be seen from Fig. 3, in what manner they lie side by side. These arms 25, which carry the bearings for the retention 105 of the two adjacent parts of the strip to be separated from each other during the separating process, stand with their freely-oscillating end 26 under the influence of springs 27, which are fastened to the arms 28, attached to the frame portion 29. The springs 27 normally hold the arms 25 in the lifted position shown in Fig. 4. The bearings 30, attached to the two arms 25, serve to hold fast the advanced portion of the band and that 110 which is attached thereto during the separating process. This is effected in that the two bearings 30 on pressing down the lever 25 are pressed against the two parts 31, Fig. 9. Between the two levers or cheek-carriers 25 and between the two cheeks 31, lying below the stamp, there is room for the play of the separating-tool 32, which is preferably blunt. This is rotatably mounted on the frame 29 at 115 33 and is held in the inoperative position by the spring 34. As the end of the band, owing to the separating process, inclines slightly downward, there is provided, in order to pre- 120

vent upon the next feed movement any contact thereof with the part 31, a weak plate-spring 93, which guides the end of the band upward again immediately after the back travel of the knife. The levers 25 are furthermore connected at 36 through the springs 35 with the lever 3, which forms the continuation of the aforesaid lever 22. The fastening of the spring 35 to the lever-arm 3 is effected at 37. This carries the pressure-roller 38 into such a position that it can come in contact with the back of the separating-tool 32 when the lever 3 is moved in the direction of the arrow IV.

15 The method of operation of the separating and the holdfast device is as follows, according to Fig. 4: If by means of the change-wheel 20 the lever-arm 22 be moved forward in the direction of the arrow V, then the lever-arm 3 will execute a swinging movement in the direction of the arrow IV. Hereby the spring 35 is first expanded or set, and thus causes the downward movement of the arms 25, so that the cheeks 30 press against the part 31. Directly after this has taken place the pressure-roller 38 comes in contact with the back of the separating-blade 32 and presses this downward, Fig. 10, whereby the separation of the part to be sold is effected, 30 Fig. 9. The distance between the fixing or clamping devices 30 31 is greater than the thickness of the separating-tool. This arrangement affords advantages from several points of view. In the first place a relatively-blunt 35 tool can be used, as the separation of the portion to be sold is not effected by a cutting or slicing off, but by means of a tensile spring. The strip of stamps is firmly stretched between the fixing device 30 31, so that the 40 blunt knife 32, pressing upon the band, stretches the band tight. As this tension is distributed over a considerable length of band, it is assured that a springing off or coming apart will take place at the weakest part 45 or point of perforation if this should not lie immediately beneath the knife. In this way a guarantee is afforded for an always correct separation of the stamp.

As already mentioned in the introduction, 50 it is important that the separating process should take place directly after the commencement of the forward movement of the delivery-slide, because the movement of the delivery-slide affords the greatest amount of 55 resistance. In order, however, that the portion cut off may not freely fall down at once and be placed at the purchaser's disposal before the delivery-slide *a* has been completely drawn or pushed out of the apparatus, the release of the holdfast device does not take 60 place till the delivery-slide *a* has entirely completed the movement hereinbefore described. This does not offer any difficulties if the change-wheel 20 be made in such a way 65 that the pressure-roller 21 remains in the

lifted position till the slide *a* has entirely completed its travel. This latter problem is solved according to Figs. 5 and 6, in that the eccentric teeth 40 of the change-wheel 20 have been given a suitable form. Normally 70 speaking, the pressure-roller 21 lies in the recesses 41. Furthermore, the locking-wheel 19 is so arranged that upon the complete forward movement of the slide *a* it is moved farther forward by the length of one tooth or by 75 the length of a certain number of teeth, corresponding to the spacing (or distance between) of two successively following recesses 41 of the change-wheel 20. If, as per Figs. 5, 6, the slide *a* be moved in the direction of the arrow 80 I, then the ratchet-wheel 19 and the change-wheel 20 will be carried along with it in the direction of the arrow. Hereby the pressure-roller 21 is lifted by the eccentric teeth 40, this latter being formed in such a way that 85 the release of the pressure-roller 21 for the engagement with the next recess 41 can take place when the slide *a* has completely terminated its travel, Fig. 5. It therefore results that the position and formation of the teeth 90 40 must have a certain relationship with the slide. If the slide *a* has terminated its forward movement and if it automatically returns in the manner to be hereinafter explained, then the lever 16, with the detent 18, 95 will also be moved back by the spring 42 from the position shown in Fig. 5 into the position shown in Fig. 6. During this time the pressure-roller 21 passes into the next recess 41, so that all the parts of the separating and 100 holdfast device again take up, under the influence of the springs 34, 35, and 27, the inoperative position (shown in Fig. 4) and leave the way clear for the feed of the next stamp.

The device for releasing the delivery-slide 105 may be seen from Figs. 2, 7, and 8. The slide *a* has a recess 45, which normally lies within the guide 46, according to Fig. 2, in such a way that the coin 48, introduced through the passage 47, is held back. The 110 coin is then in front of the free end of the lever-like part 49, sloped off in a downward direction, which is rotatable at 50. The slide *a* has, furthermore, a catch 52, which upon its forward movement, as shown in Fig. 8, 115 comes in contact with the end of the lever 49. The coin then presses against the sloped-off part 51 and lifts the lever 49, so that its end no longer lies within the scope of the catch 52, which can be drawn out without hindrance, whereupon the coin 48 falls through a passage 53 into the receiver. When the slide *a* has returned to the position shown in Fig. 2, the lever 49 again forms the locking mechanism. The spring *i*, Fig. 3, 120 125 which is set on pulling forward the slide *a*, tends to pull it back again; but this, however, after once starting the selling process cannot be effected till the slide has been entirely pulled out. For this reason a locking 130

device is located at *g*, Fig. 8, which can, for instance, be made in such a way that the slide is provided on its top side with teeth, with which a pawl engages and prevents it upon being drawn out from prematurely and automatically going back again, (Fig. 8, position shown in full line,) and also prevents it on returning from being pulled out again. (Fig. 8, position shown in dotted lines.) The change of position of the pawl *G* is effected upon termination of the slide travel in the one or the other directions by means of the two recesses 55 56. The back travel of the slide *a* takes place after the reversal of the locking device under the influence of the stress of spring *i*; but any violent recoil is prevented by means of an air-cushion *K*, which consists of a plunger and a cylinder mounted upon the slide and provided with air-outlets in the known manner. There is also an arrangement provided by means of which the placing in motion of the self-vending machine is prevented as soon as the store of goods is exhausted—that is to say, when there are no more strips of stamps at disposal. For this purpose there is used a two-armed lever 58, Fig. 3, which is rotatable at 59 and which rests loosely upon the band with one of its ends, which is provided with a pin or the like. When the last stamp or last portion to be separated from the band or strip to be cut off has passed under the lever 58, the latter rotates on fulcrum 59, so that its nose 61 enters a slot in the coin-chute 47, Fig. 1, and prevents any coin that may have been inserted from falling into the recess 45. Thus the coin may be conducted into another chute or passage and returned to the outside of the machine.

From what has been said above the method of operation of the automatic vending-machine hereinbefore described—for instance, for the sale of stamps—may be briefly summarized as follows: After unlocking, the forward movement of the slide *a* can take place in the direction of the arrow *I*, releasing the locking devices 49 50 51, Fig. 2. At the same time the stretching tight of the stamps is effected by means of the levers 28 25, and thereupon the separation is effected by the descent of the blade 32 under the influence of the change-wheel 20, rotated by the shoulder 14 of the slide *a*. During the forward movement of the slide the feeding device 56 7 is moved back by the agency of the lever *e*. Not until the forward movement of the slide *a* is the tension and holdfast device released by the change-wheel 20, whereby the passage is left clear for the further onward movement of the strip. Not till then does the purchaser receive the falling stamps, which can be conducted in any suitable manner to a passage leading to the point of delivery, and at this moment the purchaser releases his hold of the slide *a*. At the end of

the forward movement of the delivery-slide the locking device *g* is also reversed, so that said slide *a* can be moved freely backward under the influence of the spring *i* and the air-cushion *K*. At the same time there takes place the forward movement of the feed device 56 7, which induces the forward movement of the strip of stamps to the extent of the length of one stamp, whereby the apparatus is made ready for the next sale.

The constructional form shown may be modified in many ways without the spirit of the invention being altered thereby.

I claim—

1. In a machine for vending stamps or like articles in band or strip form, the combination of a hand-operated slide, guides for the stamp-band, a rotatable wheel having peripheral projections and operatively connected with the hand-slide, a pivoted lever one end of which rides on said wheel, a stamp-separating device actuated by said lever as the latter tilts, a vertically-movable presser which is normally spring-supported and operatively connected with the aforesaid lever so that it is depressed to clamp the stamp-band when the lever tilts and before the stamp-separator acts, substantially as described.

2. In a machine for vending stamps or like articles in band or strip form, the combination of a hand-operated slide, guides for the stamp-band, a rotatable wheel having peripheral projections and operatively connected with said slides, a stamp-separating device operated by said wheel, means for clamping the stamp-band just previous to the operation of the separator, and a spring connecting the latter with the clamp whereby they are operated together and one in advance of the other, substantially as described.

3. In a machine for vending stamps or like articles in band or strip form, the combination of a hand-operated slide, guides for the stamp-band, slidable feeding devices adapted to engage the band for carrying it forward intermittently, a pivoted lever connecting the said slide with the stamp-feeder whereby the feeder is advanced as the slide is retracted, and means for clamping the stamp-band preparatory to separating a stamp therefrom, a stamp-separator, and means for operating the clamp and separator, the same being connected with the slide, substantially as described.

4. In a machine of the character described, the combination with a guide-passage for the perforated stamp-band and means for temporarily clamping said band and means for separating individual stamps therefrom, of a feed device and means for reciprocating it, said device consisting of a series of pivoted teeth which operate independently of each other and work in frictional contact with the band so as to engage holes therein when

moved forward and slide free over said band on the return movement, as shown and described.

5. In a machine of the character described the combination with a guide for the perforated stamp-band, a pivoted feed device and a means for actuating it, of a spring 92 which serves, after the feed device has passed beyond the central position to throw said device into an inclined and normal position, as shown and described.

6. In a machine of the character described the combination with a guide for the perforated stamp-band and means for clamping it at points separated from each other, of a separating device which acts between the clamps, and means for actuating it, as described.

7. In a machine of the character described, the combination of a stamp-separating device, means for temporarily holding fast the perforated stamp separated from the band, a slide *a* and means which connect with and serve to close the clamping means and a device which acts on the separating device subsequently to the closure of the clamp so that release of the separated stamp to be sold does not take place till after termination of the forward movement of the slide, as described.

8. In a machine of the character described, the combination of a slide *a*, means for clamping a perforated stamp-band, a device for separating from the band a stamp to be sold, a lever, and a rotatable member for actuating the separating device which is interposed between said slide and the band-clamp, as shown and described.

9. In a machine of the character described, the combination of a slide, pivoted band-clamping members 25, 30, 31, arranged side by side, a pivoted separating-blade arranged to act between them, a pivoted lever arranged to act on said separating device, and a toothed wheel acting on the lever, a spring connecting the outer end of said lever with the clamping members and means for operatively connecting the slide and notched wheel whereby the band-clamp is first closed and the separating device actuated subsequently, as described.

In testimony whereof I have hereunto set my hand, in presence of two subscribing witnesses, this 8th day of September, 1903.

WILLY ABEL.
